United States Patent Office.

ALVA C. BULLOCK, OF NORTH PROVIDENCE, RHODE ISLAND.

Design No. 3,556, dated June 29, 1869.

DESIGN FOR A CROQUET-MALLET.

The Schedule referred to in these Letters Patent and making part of the same.

To all whom it may concern:

Be it known that I, ALVA C. BULLOCK, of North Providence, in the county of Providence, and State of Rhode Island, have originated and designed a new Pattern for Croquet-Mallets, of which the following is a full, clear, and exact description, reference being had to the accompanying drawing, making part of this specification.

It will be observed the mallet is turned with its ends tapering downward from near the centre.

Encircling the mallet, equidistant from the ends, is

a concave recess, suitably lined, as shown, the whole forming a mallet with neat, elegant, and attractive outline.

What I claim as my invention, and desire to secure by Letters Patent of the United States, is—

The design for a croquet-mallet herein described.
ALVA C. BULLOCK.
